DESIGN FOR AN INDUSTRIAL TRUCK

Glen Holland, Bronxville, N. Y., and Herbert J. Framhein, Chicago, Ill., assignors to The Yale & Towne Manufacturing Company, Stamford, Conn., a corporation of Connecticut

Application April 18, 1942, Serial No. 106,622

Term of patent 14 years

To all whom it may concern:

Be it known that we, Glen Holland and Herbert J. Framhein, citizens of the United States, residing, respectively, at Bronxville, in the county of Westchester and State of New York, and at Chicago, in the county of Cook and State of Illinois, have invented a new, original, and ornamental Design for an Industrial Truck, of which the following is a specification, reference being had to the accompanying drawing, forming part thereof.

Fig. 1 is a top plan view of an industrial truck showing our novel design.

Fig. 2 is a side elevational view, and

Fig. 3 is a front elevational view thereof.

We claim:

The ornamental design for an industrial truck, as shown.

GLEN HOLLAND.
